ILLUMINATED DISPLAY

Frederick A. Sunderhauf, Rutherford, N. J., assignor to Reynolds Metals Company, Richmond, Va., a corporation of Delaware

Application April 7, 1939, Serial No. 266,459

2 Claims. (Cl. 40—133)

This invention relates to an improved collapsible, or knock-down, display giving unique "colored" and "white" light effects, and particularly adapted to give a glowing "neon" effect at night and also to provide a sign for both day and night use, and is to be regarded as an improvement of the class of illuminated signs described in claims in the United States Patent No. 2,086,893, issued July 13, 1937, to Charles W. Belden, and in United States Patent No. 2,148,179, issued February 21, 1939, to Frederick A. Sunderhauf, the present inventor.

Heretofore various illuminated displays have been suggested but these commonly have been expensive to fabricate and difficult to assemble. Certain of the displays incorporated breakable glass parts and others were not attractive or attention compelling.

Therefore, it is an object of my invention to die cut and die score preferably metal foil covered cardboard into several simple parts, which can be easily and economically factory joined together into a flat collapsible or knock-down display, and which may be easily assembled to upright display position for counter or window display use. Also, it is an object of my invention to provide a unique attention compelling display which will combine preferably the illumination by white light of a translucent screen incorporating an artistic design by means of preferably a single electric light bulb, which bulb can be also utilized to illuminate by reflective colored light, in one or more colors, depending upon the reflective colored background, a stenciled sales message, or advertisement.

It is a further object of my invention to manufacture flat collapsible displays of this class in large quantities economically and in such fashion that when assembled in upright display position, displays are strong and stable and attractive.

It is a further object of my invention to manufacture displays of this class of a main die cut and stencilled main body portion, or front panel portion, a rear flexible and collapsible reflective portion, and preferably two "tension" members, hinged to the main body portion and adapted to tension against the rear portion to maintain the same in an effective reflective position and to stabilize the display.

These and various other objects and advantages will be readily understood from the following description taken in connection with the accompanying drawing of preferred embodiments in the invention, in which modifications may be

made without departing from the scope of the appended claims.

In the drawing:

Fig. 1 is a perspective of a display embodying my invention, showing a stencilled sales message, adapted to be illuminated by reflective colored light, and a translucent screen portion incorporating an artistic design, adapted to be illuminated by normal light emanating from an ordinary electric light bulb, namely, by "white" light.

Fig. 2 is a side elevation, partly broken away, of the display illustrated in Fig. 1.

Fig. 3 is a section taken on the line 3—3 of Fig. 2.

Fig. 4 is a section taken on the line 4—4 of Fig. 3.

Fig. 5 is a perspective, partly broken away, of the display illustrated in Fig. 1, in flat collapsed form, suitable for wrapping for shipment.

In these figures, a main body or display panel portion 10 will ordinarily be die cut from a stiff cardboard or like paper or other stock in such fashion as to provide a stencilled sales message, and in the form illustrated, this sales message is shown in two lines, "Steamship" identified as 12 and "Line" indicated as 14, and also die cut to provide an opening, preferably of rectangular shape, indicated as 16.

The opening 16 may be covered by a translucent paper 18 or the like, bearing an artistic design such as the steamship illustrated.

A flexible reflective backing member indicated as 20 will normally be made from a single integral piece of light paper stock so that the same may be flat collapsible as indicated in Fig. 5 with a folding line 22. The said marginal edges of reflective backing member 20 will be united to the marginal edges of the main display member 10 by adhesive 24 as indicated.

The member 20 will normally assume a generally circular or parabolic curved form, when the display is assembled, in order to provide a good reflective surface for the electric light bulb 26, and this form will be assumed by member 20 by virtue of tension applied thereto by hinged members 28 and 30. Foldable hinged members will normally be mounted to front panel portion 10 by adhesive, or other mounting means, the member 28 being towards the top of the display above stencil 12 and the lower member 30 being towards the bottom of the display beneath opening 16.

Ventilating openings 32 and 34 may be provided in members 28 and 30 as indicated.

Also, electrical socket hinged flange members 36 will be die cut and die scored from member 30.

Members 28 and 30 are positioned in a plane 5 perpendicular to the plane of front panel portion 10 when the display is assembled and these members tend to retain reflective member 20 in the desired reflective form.

Slots 38 and 40 will be provided in rear member 20 and projections 42 and 44 upon members 28 and 30 respectively will fit into the said slots, thus giving a rigid and stable construction to the display when the same is assembled.

The interior surface of flexible reflective backing member 20 may be divided into three distinct reflective portions: namely, a portion identified as 46 which may be colored blue to reflect light from bulb 26 through stencil openings 12; a portion identified as 48 which may be colored red to 15 reflect colored light from bulb 26 through stencil openings 14 and a colorless, or white reflective area identified as 50 to reflect normal "white" light through the translucent panel 18 which bears an artistic design. By this arrangement, I 20 provide, from a single light bulb, two different colored lights projected through stencil openings 12 and 14 and a normal white light through translucent screen 18.

The commercial aspect of the present invention 30 will be readily realized by those skilled in the art because by the provision of a simple flat collapsible sign formed of four main cardboard members, an attention compelling display may be manufactured from a die cut and die scored 35 cardboard stock easily, economically, and rapidly, the illumination all emanating from an ordinary electric light bulb of relatively low wattage.

Various modifications may be made in the display as described, it being realized that my invention involves the projection of white and colored lights through various die cut openings and also a simple die cut, preferably metal foil covered, cardboard display panel member arranged with hinged support members and a collapsible rear reflective member.

It will be understood that while the illustrated form of the invention which I have described represents a preferred embodiment, I do not wish to limit myself to the details as shown, since it is obvious that the same may be widely varied 5 without departing from the spirit of the invention as described and claimed in the appended claims.

I claim:

1. In a display, a main display panel formed 10 of cardboard or like stock, having a plurality of die cut openings clearly separated one above the other, a collapsible rear reflective member adapted to be folded flat, collapsible tension members hingedly connected to said main panel and adapted to tension the said reflective member into a curved reflective form, a plurality of reflective colors in preselected areas of said reflective member arranged relative to said die cut openings so that at least one of the openings is illuminated 20 by a different colored light than the other openings, an electric light bulb means of illumination between the display member and the reflective member, and a translucent screen bearing an artistic design covering one of said openings. 25

2. In a display, a main display panel formed of cardboard or like stock, having a plurality of die 30 cut openings clearly separated one above the other, a collapsible rear reflective member adapted to be folded flat, collapsible tension members hingedly connected to said main panel and adapted to tension the said reflective member into a curved reflective form, a plurality of reflective colors in preselected areas of said reflective member arranged relative to said die cut openings 35 so that at least one of the openings is illuminated by a different colored light than the other openings, an electric light bulb means of illumination between the display member and the reflective member, and a translucent screen bearing an artistic design covering one of said openings. 40
